UNITED STATES PATENT OFFICE.

WILSON E. FACER, OF CLEVELAND, OHIO.

OIL-BURNER.

SPECIFICATION forming part of Letters Patent No. 397,493, dated February 12, 1889.

Application filed November 14, 1887. Serial No. 255,151. (No model.)

To all whom it may concern:

Be it known that I, WILSON E. FACER, of Cleveland, in the county of Cuyahoga and State of Ohio, have invented certain new and useful Improvements in Oil-Burners; and I do hereby declare the following to be a full, clear, and exact description of the invention, such as will enable others skilled in the art to which it pertains to make and use the same.

My invention relates to improvements in oil-burners designed more especially for crude hydrocarbon oil; and it consists in certain features of construction and in combination of parts hereinafter described, and pointed out in the claims.

In the accompanying drawings, Figure 1 is a side elevation in section through the center of the burner. Fig. 2 is a plan below line *xx*, Fig. 1, the same being partly in section. Fig. 3 is a plan of the central portion of the supporting-plate. Fig. 4 is a bottom plan of the central portion of casing B.

A represents a supporting-frame that may be of any suitable form, the top plate of which has an opening, A', for receiving the hollow depending annular flange B' of the cup-shaped casing B. The latter near the top has an external annular flange, B², for supporting the top section, B³, of the casing, the latter being preferably of tubular tile or fire-brick. Internal grooves, a, in plate A on opposite sides of opening A', holes b in casing B, and external groove, b', in flange B' are for the passage of steam-pipe C and water-pipe D, these pipes being secured by set-screws a'. These pipes screw into and support the steam-generator E, the latter being preferably of about the form shown in Fig. 1, in which the hollow cylindrical section E' and the concaved bottom E² are screwed together. Pipe C has an extension, C', that extends to near the top of the generator. The upper pipe fits inside the lower pipe, so that it may turn therein, otherwise, owing to the lateral deflection of the upper pipe and the proximity of the side of the cone, the lower pipe could not be screwed into the bottom plate, E², of the generator. Pipe C, at the lower end thereof, screws into and supports the lighting-cup F. The latter is provided with a duct, f, leading from pipe C to the discharging-orifice f', this

orifice presenting upward and being located centrally relative to the opening inclosed by flange B'. The upright and lateral sections 55 of water-pipe D are connected by an elbow-fitting, D', the latter having a valve, d, for controlling the flow of water through this pipe. The oil-supply pipe G screws into fitting G', the latter being provided with valve 60 g and discharging-nozzle g', the jet-orifice of the latter being located over and in close proximity to the steam-discharging orifice f'.

H is a deflector, usually made of cast-iron and used only in case it is desired to deflect 65 the heat laterally. The deflector is mounted loosely on a stud or plug, h, the latter screwing into the top of the generator, with a sleeve, h', of sufficient length to give the necessary elevation to the deflector. Two or 70 three such sleeves, but respectively of different lengths, are usually provided, so that the distance of the deflector above the burner may be varied according to circumstances. Some little pressure of oil and water is required, such as would be had by elevating 75 the oil and water tanks (not shown) perhaps three feet (more or less) above the burner.

In operating the device, first valve g is opened to fill the lighting-cup with oil, after 80 which this valve is closed and the oil in the lighting-cup is lighted. The products of combustion pass up through the opening in the flange B' and impinge the bottom of the steam-generator and envelop the portions of 85 pipes C and D that protrude above the casing and envelop the sides of the generator, so that by the time the oil of the lighting-cup has partially burned out the generator will have been highly heated. Next, by opening 90 valve d a trifle a very limited quantity of water is admitted to the generator, and as this water trickles down the concavity of bottom section, E², the water is almost instantly converted into steam and in such condition 95 enters pipe C' and flows out of the orifice f'. As soon as a goodly volume of steam is seen escaping, valve g is opened a trifle to admit a limited quantity of oil, which latter is discharged directly into the steam-jet and substantially at right angles to the latter. The steam-jet instantly atomizes and presumably vaporizes the oil, and this oil product, with the flames from the lighting-cup, results in 100

an intense heat and a large volume of flame that fills the casing B, so that by the time the oil in the lighting-cup has been exhausted, or soon after, the steam-generator becomes red-hot. The latter would indicate that there was no body of water in the steam-generator, but that each drop that came in contact with such red-hot bottom was converted into superheated steam. After the oil in the lighting-cup is burned out and the steam-generator has become sufficiently heated, valves *d* and *g* are manipulated to regulate the supply of water and oil as required; but far better results are had, according to the amount of oil used, where the generator is kept at a red heat. With such practice the steam-generator will in time burn out; but if it is made of malleable cast-iron it can be renewed at a trifling cost. The combustion seems to be perfect, so much so that with a large-sized burner operating for several hours without a flue and in a closed room no smoke, odor, or condensed vapors were perceptible. With this burner the great amount of heat developed as compared with the small amount of oil consumed induces me to believe that the steam is decomposed by the heat and that the component gases thereof, oxygen and hydrogen, unite and burn with the oil-vapor together with oxygen from the current of air drawn into the burner by means of the steam-jet.

To insure an instantaneous and thorough commingling of the steam and oil, I provide a small upright conical nozzle, *I*, integral with and supported by a sleeve, *i*, the latter being mounted on nozzle *g'*. The lower larger end of nozzle *I* is directly over and close to orifice *f'*.

The atomized oil or oil-vapor, whichever it may be, and the steam as they pass through nozzle *I* are forced into such close relation that they thoroughly and instantaneously commingle. I may add that whatever pressure of steam may be required is had by giving the water-tank the necessary elevation to produce such pressure.

What I claim is—

1. The combination, with a steam-generator, a steam-discharging pipe leading therefrom, and a water-supply pipe in open communication therewith, said steam and water pipes forming a rigid support for the generator, of oil-discharging orifice in the line of the steam-jet approximately at right angles thereto, and a lighting-cup located below the burner, said cup having a duct therein out of which the discharge-orifice leads, this duct being in open communication with the steam-pipe, substantially as set forth. 60

2. The combination, with a sectional steam-generator, a water-supply pipe, and a steam-discharge pipe leading in and out of the said generator, of oil-discharging orifice located in line of the steam-jet approximately at right angles thereto, and a lighting-cup attached to and supported by the steam-pipe, said cup having a duct therein in open communication with the steam-pipe and out of which the discharge-orifice leads, substantially as set forth. 70

In testimony whereof I sign this specification, in the presence of two witnesses, this 2d day of November, 1887.

WILSON E. FACER.
